REMOVABLE HEAD FOR METAL CONTAINERS AND SEALING MEANS THEREFOR

Louis B. Wackman, St. Louis, Mo.

Application January 2, 1934, Serial No. 704,842

9 Claims. (Cl. 220—61)

This invention more particularly relates to a container or drum which is closed on its chime by a removable head having securing means for effecting a fluid tight joint between the head and the chime.

An object of the invention is to provide an improved operating mechanism for the securing band of the removable head and container chime.

Another object of the invention is in providing a split securing band for the heads and chimes of containers having an improved operating mechanism therefor, carried by one end of the band and the mechanism having detachable connecting means for the other end of the band.

A further object of the invention is in providing a band sealing and locking device with an operating mechanism having means which are cooperable to contract the band before the locking means of the mechanism is effected.

The invention has for another object to provide an improved head and chime securing and locking device which forms part of the container or drum, with a foldable lever actuating mechanism.

Other and further objects will appear in the specification and be specifically pointed out in the appended claims, reference being had to the accompanying drawing, exemplifying the invention, and in which:—

Figure 1 is a plan view of an embodiment of the invention showing its application to the head of a container for securing and locking the head to the chime.

Figure 2 is an enlarged vertical section taken through the upper end of the container on the line II—II of Fig. 1.

Figure 3 is an enlarged transverse vertical section taken through the securing and locking band showing the operating mechanism in a released position.

Figure 4 is an enlarged fragmentary plan view of the split ends of the securing and locking band.

Figure 5 is an enlarged fragmentary vertical section taken approximately on the line V—V of Fig. 2.

Figure 6 is an enlarged fragmentary vertical section taken approximately on the line VI—VI of Fig. 2.

Figure 7 is an enlarged fragmentary vertical section taken approximately on the line VII—VII of Fig. 1.

Figure 8 is an enlarged fragmentary vertical section taken approximately on the line VIII—VIII of Fig. 1 showing the operating

mechanism in a position of disengaging the links of the band from the locking pin.

Referring to the drawing, 1 indicates the container or drum having the vertical wall 2, the upper end of said wall having a rolled portion formed 5 annularly therearound for providing a bead 3 which constitutes the chime of the container.

A removable counter-sunk head 4 having a vertical wall 5 with a surrounding outwardly extending horizontal marginal flange 6, is provided 10 for cooperation with the container chime, and formed in the wall 5 of the head is an annular groove 7 for the support of a sealing gasket 8.

For securing the head 4 to the chime after the container 1 has been filled, a split locking band 9 is provided, said band being of a channel shape in cross section and having the ends 10 and 11 adjacent the split of the band, each of said ends having an inwardly projecting horizontal portion 12 extending from the top side of the band, the portion 12 of the end 10 having a downwardly extending part 13 which is of a depth to engage the counter-sunk part 4a of the head.

Secured to the depending part 13 in straddling position thereto by the pin 14 are the ends of a 25 pair of links 15, the opposite ends of said links bearing a pin 16 which provides a fulcrum for an operating lever 17, said lever being mounted on the pin 16 between said links and is provided with a toe portion 18 there adjacent.

The horizontal portion 12 of the band and 11 is provided on its inner end with a U-shaped bracket 19 which is adapted at its lower end to engage the counter-sunk portion 4a of the head 4, the opposing walls of said bracket supporting 35 a rivet or pin 20, said bracket being for the reception of the swinging ends of the links 15 when the band 9 is being contracted.

In mounting the securing band 9 over the flange 6 of the head 4 and the bead 3 of the container, the lever 17 and the links 15 connected therewith, are swung to the position shown in full lines in Figs. 3 and 4. This released position of the lever 17 provides for the band 9 to be expanded by reason of the split thereof, so that 45 the band can be aptly and readily mounted in position over the flange of the head and the bead of the chime of the container. After the band has been mounted in position as just described, and as securing bands of this character will be 50 made in sizes to accommodate different sizes of containers, the lever 17 is engaged and swung with the links 15 on the pin 14, downwardly towards the bracket 19, and the toe portion 18 is engaged on the far side of the pin 20 of the 55

bracket as shown by dotted lines in Fig. 3. The lever 17 is then swung on the pin 16 of the links 15 and the toe portion 18 of the lever will be forced to ride under the pin 20 of the bracket 19 and the pin 20 will be seated in the dwell recess 21 of the lever 17, the toeing action of the portion 18 on the pin 20 of the bracket, drawing the ends 11 and 10 of the band 9 towards each other thereby contracting the band.

10 Continued downward swinging movement of the lever 17 will draw and lower the links 15 to a position in the bracket 19 until the aligned recesses 22 on the lower edges of said links will ride in over-engagement with the pin 20 of the bracket 19, and in this position of engagement of the recesses 22 of said links with the pin 20, the lever 17 will have been lowered to a horizontal position, and the engagement of the links 15 with the pin 20 will provide a lock against a springing releasing force being self applied by the lever 17. Further, there can be no sprung upward movement given to the links 15 where they connect at 16 to the lever 17 by reason of the toe portion 18 of the lever under-engaging the pin 20 of the bracket 19, when the lever is secured and sealed by the disc-like member 24 and sealing wire 28.

The swung down horizontal position of the lever 17 will place the handle extending end of the lever in proximity to the bracket 23, said bracket having a disc-like member 24 swingably connected to it by a rivet 25, which is adapted to be engaged in a bifurcation 26 by manipulating the handle 27 of said member, said member when engaged in the bifurcation, having its handle 27 in approximate abutment with the lever 17 and is secured to the lever 17 by a sealing wire 28 which is passed through an aperture in the handle 27 and an aperture in the lever 17.

40 The disc-like member 24 when secured in engagement with the lever 17 provides for securing the lever against unauthorized manipulation after the band 9 has been secured in sealing position.

45 By reason of the operating mechanism being secured at right angles to the top side of the band 9, the actuating effort will be directly against and on top of the band and in a proper direction for forcing the band downwardly over the bead 3 of the container chime, thereby assisting the creeping or drawing action required in contracting or drawing the band in securing position.

50 For removing the band 9 from its securing position over the container chime and head, the sealing wire 28 is broken and the lever 17 is swung upwardly to the position shown in full lines in Fig. 3. During the upward swing of the lever 17 on the pin 16 of the links 15 for expanding the band for removal, the toe portion 18 of said lever will be first caused to engage the bottom of the bracket 19 and thus force or pry the ends of the links 15 where they connect at 16 to said lever, upwardly, and dis-engage the recesses 22 thereof from the pin 20 of the bracket 19 in the manner as shown in Fig. 8.

55 Obviously constructional modifications of the device are possible without departing from the spirit of the present invention and therefore it is to be understood that it is not necessary to limit the invention by the terms used in the foregoing description, excepting such as the state of the art may require.

60 What I claim is:

65 1. In a clamping device for a metallic container having a bead rolled about its open end

and a cover having a flange fitting over the bead, a contractile split channeled band to press the bead and the cover flange together when the band is contracted, and means for contracting the band comprising a recessed link connected to one end of the band, a pin connected to the other end of the band for cooperation with the recess of said link, and a lever connected to said link having one end detachably cooperable with the pin on the other end of the band.

70 2. In a clamping device for a metallic container having a bead rolled about its open end and a cover having a flange fitting over the bead, a contractile split channeled band to press the bead and the cover flange together when the band is contracted, and means for contracting the band comprising a pair of paralleling recessed links connected to one end of the band, a pin to be engaged by the recesses of said links connected to the other end of the band, and a lever connected between said links having one end detachably cooperable with said pin, said lever and said links being disposed to operate at right angles to the band, for drawing the links to engage the recesses thereof with said pin.

75 3. In a clamping device for a metallic container having a bead rolled about its open end and a cover having a flange fitting over the bead, a contractile split channeled band to press the bead and the cover flange together when the band is contracted, and means for contracting the band and simultaneously exerting a downward pressure against the band comprising a recessed link connected to one end of the band, a pin connected to the other end of the band for cooperation with the recess of said link, and a lever connected to the link having one end detachably cooperable with the pin on the other end of the band for drawing the link to engage the recess thereof over said pin.

80 4. In a clamping device for a metallic container having a bead rolled about its open end and a cover having a flange fitting over the bead, a contractile split channeled band to press the bead and the cover flange together when the band is contracted, and means for contracting the band and simultaneously exerting a downward pressure against the band comprising a recessed link connected to one end of the band, and a lever connected to the link having one end detachably cooperable with the other end of the band, said lever and said link being disposed to operate at right angles to the band, for engaging the recess of said link over a part of said band.

85 5. A clamping device for securing heads to metal containers comprising a split channeled band, a link connected to one end of said band and a lever having a toe end connected to said link, the other end of the band having a part to be cooperably engaged by the toe end of said lever for contracting the band, and means on the link for engagement with said part for holding the band in contracted position.

90 6. A clamping device for securing heads to metal containers comprising a split channeled band, a link connected to one end of said band and a lever having a toe end connected to said link, the other end of the band having a part to be engaged and subsequently underengaged by the toe end of said lever during contracting of the band, and means on the link for over-engagement with said part for holding the band in contracted position.

95 7. A clamping device for securing heads to metal containers comprising a split channeled

band, a link connected to one end of said band and a lever having a toe end connected to said link, the other end of the band having a part to be engaged and subsequently underengaged by the toe end of said lever during contracting of the band when the lever is actuated for contracting the band, and means on the link for over-engagement with said part, the under-engaging of the toe end of the lever and the over-engaging of the means on said link with respect to said part, providing a lock for the ends of the band when the band is contracted.

5 8. A clamping device for securing heads to metal containers comprising a split channeled band, a link connected at one end to an end of said band and a lever having a toe end connected to said link, the other end of the band having a part to be under-engaged by the toe end of said lever when the lever is actuated in one direction, and a recess on the link for over-engagement

10 with said part, the toe end of said lever being cooperable to cause the lever to move the link for dis-engaging the recess thereof from said part, when the lever is actuated in the other direction.

15 9. A clamping device for securing heads to metal containers comprising a split channeled band having a bracket at one end, a link connected at one end to an end of said band and a lever having a toe end connected to said link, a pin carried by said bracket to be under-engaged by the toe end of said lever when the lever is actuated in one direction, and a recess on the link for over-engagement with said pin, the toe end of said lever being cooperable with said bracket to cause the lever to move the link for dis-engaging the recess thereof from said pin, when the lever is actuated in the other direction.
